ELECTRIC SWITCH BUTTON

Wesley T. Sorenson, West Hartford, Conn., assignor to
Sorenson Lighted Controls, Inc., West Hartford, Conn.,
a corporation of Connecticut

Continuation of design applications Ser. No. 71,502,
Aug. 30, 1962, and Ser. No. 71,526, Sept. 4, 1962.

This application Dec. 11, 1963, Ser. No. 77,883

Term of patent 14 years

(Cl. D26—13)

FIGURE 1 is a front elevational view of an electric switch button showing my new design wherein one window is disclosed;

FIGURE 2 is a side elevational view thereof;

FIGURE 3 is a top plan view of the button shown in FIGURE 1;

FIGURE 4 is a cross-sectional view taken on lines 4-4 of FIGURE 1 and looking in the direction of the arrows;

FIGURE 5 is a front elevational view of an electric switch button showing another form of the design wherein two windows are disclosed;

FIGURE 6 is a side elevational view of the button shown in FIGURE 5;

FIGURE 7 is a top plan view of the button shown in FIGURE 5; and

FIGURE 8 is a cross-sectional view taken on the lines 8-8 of FIGURE 5 and looking in the direction of the arrows.

The face plate shown in broken lines in the drawings is for illustrative purposes only.

The essential features of my design comprise a switch-button having a pair of adjacent V-angle surfaces and a horizontal window located either in one or both of said surfaces.

This application is a continuation of the present applicant's both copending applications: Serial No. D. 71,502, filed August 30, 1962, and Serial No. D 71,526, filed September 4, 1962, both now abandoned.

I claim:

The ornamental design for an electric switch button, substantially as shown and described.
